PLATE CLAMP FOR PLATE CYLINDER OF
PRINTING PRESSESHarry W. Faeber, Larchmont, N. Y., assignor to
Time, Inc., New York, N. Y., a corporation of
New York

Application December 26, 1947, Serial No. 793,778

8 Claims. (Cl. 101—415.1)

1

The present invention relates to mechanisms for securing printing plates to the plate cylinders of printing presses and embodies more specifically an improved mechanism by means of which both ends of a flexible printing plate are effectively clamped in position upon the plate cylinder upon movement of the plate into its final printing position on the cylinder.

A further object of the present invention is to provide a plate clamp of the above character, wherein a common clamp mechanism is provided for securing both ends of the printing plate to the plate cylinder, the mechanism being rendered operative upon movement of the printing plate into its printing position on the plate cylinder.

Yet another object of the invention is to provide a device of the above character wherein the printing plate is clamped effectively to the printing cylinder with its ends in juxtaposed position and with all printing portions of the plate supported effectively in printing position.

Further objects of the invention will be apparent as it is described in greater detail in connection with the accompanying drawings, wherein

Figure 1 is a plan view of a plate cylinder of a printing machine, showing the plate clamp thereon in printing position with portions broken away to illustrate the details of the cylinder and clamping mechanism;

Figure 2 is a view in end elevation showing the cylinder of Figure 1;

Figure 3 is a view in transverse section, taken on line 3—3 of Figure 1, and looking in the direction of the arrows;

Figure 4 is an enlarged detail view of the part shown in Figure 3 and illustrating the manner in which the printing plate is preliminarily inserted over the plate cylinder prior to clamping it into printing position;

Figure 5 is a view similar to Figure 4 showing movement of the plate clamp toward its clamping position and wherein the clamping mechanism begins to engage both ends of the plate simultaneously;

Figure 6 is an enlarged view of the clamp mechanism shown in Figure 3, and illustrating the position of the clamp when it is locked in normal printing position; and

Figure 7 is a view in section, taken on line 7—7

2

of Figure 4, and showing the fixed end of the printing plate as it is mounted over the mating lip of the plate cylinder.

Referring to the above drawings, the side frames of a printing machine are illustrated at 10 and 11, as being provided with bearings 12 within which the shaft 13 of a plate cylinder 14 is received. The plate cylinder may be solid or may be fabricated from a plurality of elements, these details of the cylinder forming no part of the present invention.

At one point on the periphery of the plate cylinder 14 (Figure 3) the cylinder is formed with an elongated channel 15 which is of a circular cross-section. The channel is also formed so that the periphery of the plate cylinder 14 cuts across and through the periphery of the circle forming the outline of the channel. In this fashion the peripheral surface of the cylinder 14 is interrupted.

Within the channel 15 an elongated shaft 16 is provided, the shaft being formed with a circular periphery 17, the center of which lies within the shaft 16, and also with a circular peripheral portion 18, the center of which is the axis of cylinder 14, when the shaft 16 is in the position illustrated in Figure 3. The periphery 18 of shaft 16 thus forms a continuation of the circular periphery of the plate cylinder 14.

The cylinder 14 is formed with a lip 19 which is adapted to receive one end of a flexible printing plate 20, as illustrated in Figure 3. The fixed end of the plate 20 is provided with a turn-back flange 21 (Figures 3 and 7) provided with notches 22. Pins 23 are formed in the underside of the lip 19, and the notches 22 register with such pins in order that the printing plate may be properly registered laterally with respect to the plate cylinder.

The shaft 16 is provided with a lip 24 having register pins 25 projecting therefrom. The movable end of the printing plate is formed with a reversely extending flange 26 having notches 27 therein which register with the pins 25 in a manner similar to that described in connection with pins 23 and notches 22.

The ends of shaft 16 extend outwardly to form stub shafts 16' (Figures 1 and 2), these stub shafts having levers 28 keyed thereto. The ends of the levers 28 are provided with flat surfaces

29 which are adapted to engage flat plates 30 secured to the shaft 13. Clamp screws 31 engage the upper surface of the clamps 28 and secure them in the clamping position, as illustrated in Figures 1 and 2. This clamping position is the position also illustrated in Figures 3 and 6.

Within the lock shaft 16 an elongated groove 32 is formed. The groove 32 receives a bracket 33 which is secured thereto by means of one or more screws 34, the bracket being provided with seating faces 35 and 36, plate 33 carries an elongated block 37 of rubber, neoprene, or other suitable yielding non-metallic material, the block 37 being vulcanized or otherwise secured to the faces 35 and 36. The block is also formed with a nose plate 38 which is vulcanized or suitably secured thereto, the plate 38 having a curved cam surface 39 formed in one side thereof, and a relatively straight plate surface 40 formed in the other side thereof.

It is important that the neoprene block 37 be shaped and supported in such fashion that pressure exerted upon the nose plate 38 by both ends of the printing plate 20 will set up direct compression forces within the block 37. Thus, it will be seen that when the clamp is in the operative position illustrated in Figures 3 and 6, the plate 40 engages the flange 26 and sets up compressive forces in the block 37 between plate 40 and face 35. The curved cam surface 39 which engages flange 21 also sets up compressive forces in the block 37 between the plate 39 and the face 36.

Instead of one continuous piece, nose plate 38 may consist of several sections, which will insure more uniform gripping of the printing plate along the cylinder due to the free alignment of the individual sections.

In operation, it will be seen that the fixed end of the plate 20 with its flange 21 is slipped over the nose 19 with the notches 22 engaging the pins 23. The other end of the plate, with its flange 26, is then slipped over the nose 24 when the clamp mechanism is in the position shown in Figure 4, the notches 27 being received over the pins 25. In this position the plate 40 engages the flange 26 and sets up compression in the block 37 between the plate 40 and the surface 35, as illustrated in Figure 4. The levers 28 are then moved into position as illustrated in Figure 2. During this movement the curved cam surface 39 engages the flange 21 of the printing plate (as illustrated in Figure 5) and then continued movement of the levers into the final clamping position causes the curved cam plate to ride beneath flange 21 and set up compression forces between plate 39 and surface 36. The neoprene block thus effectively clamps both ends of the printing plate simultaneously in the printing position, as illustrated in Figure 6. In this position the nose plate 38 serves substantially to fill the space between the adjacent ends of the printing plate. In fact, the structure may be formed to provide any desired space existing between the adjacent ends of the printing plate when clamped in printing position on the plate cylinder.

It will be observed that the operation of clamping the ends of the cylinder is accomplished automatically upon movement of the shaft 16 and levers 28 into the operative position illustrated in Figures 1, 2, and 3, and the plate is effectively held in printing position at all times while the clamp mechanism is thus secured.

While the invention has been described with 75

specific reference to the structure shown in the accompanying drawings, it is not to be limited save as defined in the appended claims.

I claim:

5. 1. A plate cylinder for printing presses comprising a cylinder adapted to be journaled in a press frame, first means on the cylinder to receive one end of a flexible printing plate thereon, a shaft journaled in the cylinder adjacent the 10 first receiving means for rotation from an open position to a closed, operating position, a groove in the shaft forming a ledge for receiving the other end of the printing plate thereover, resilient means on the shaft to clamp said other 15 end of the printing plate against said ledge and to clamp said one end of the printing plate against the first receiving means while the shaft is in a position intermediate the open and closed positions, and means to rotate the shaft to its 20 closed position to apply tension to the plate and secure it in printing position around the cylinder.

2. A plate cylinder for printing presses comprising a cylinder adapted to be journaled in a press frame, first means on the cylinder to receive one end of a flexible printing plate thereon, a shaft journaled in the cylinder adjacent the first receiving means for rotation from an open position to a closed, operating position, a groove in the shaft forming a ledge for receiving the other end of the printing plate thereover, a resilient block member in said groove to clamp said other end of the printing plate against said ledge and to clamp said one end of the printing plate against the first receiving means while the shaft is in a position intermediate the open and closed positions, and means to rotate the shaft to its closed position to apply tension to the plate and secure it in printing position around the cylinder.

3. A plate cylinder for printing presses comprising a cylinder adapted to be journaled in a press frame, means on the cylinder forming a first ledge to receive one end of a flexible printing plate, a shaft journaled in the cylinder adjacent the ledge for rotation from an open position to a closed, operating position, a second ledge on the shaft to receive the other end of the printing plate, resilient means on the shaft to clamp said other end of the printing plate against said second ledge and to clamp said one end of the printing plate against the said first ledge while the shaft is in a position intermediate the open and closed positions, and means to rotate the shaft to its closed position to apply tension to the plate and secure it in printing position around the cylinder.

4. A plate cylinder for printing presses comprising a cylinder adapted to be journaled in a press frame, means on the cylinder forming a first ledge to receive one end of a flexible printing plate, a shaft journaled in the cylinder adjacent the ledge for rotation from an open position to a closed, operating position, a groove in the shaft forming a second ledge for receiving the other end of the printing plate, a resilient block member in said groove, said block member having a metallic face plate and urging one portion of the face plate toward said second ledge to clamp said other end of the printing plate against said second ledge and to urge the other portion of the face plate toward said first ledge to clamp said one end of the printing plate against the first ledge while the shaft is in a position intermediate the open and closed positions, and means

to rotate the shaft to its closed position to apply tension to the plate and secure it in printing position around the cylinder.

5. A plate cylinder as defined in claim 1 having plate registering means on said first plate receiving means.

6. A plate cylinder as defined in claim 1 having plate registering means on the ledge for receiving the other end of the printing plate.

7. A plate cylinder as defined in claim 3 having plate registering means on at least one of said first and second ledges.

8. A plate cylinder as defined in claim 4 hav-

ing plate registering means on at least one of said first and second ledges.
